Philip S. Russel, Detroit, Mich., assignor to Detroit Lubricator Company, Detroit, Mich., a corporation of Michigan

Application March 29, 1937, Serial No. 68,460

Term of patent 14 years

To all whom it may concern:

Be it known that I, Philip S. Russel, a citizen of the United States, residing in the city of Detroit, county of Wayne, and State of Michigan, have invented a new, original, and ornamental Design for a Pressure Control Casing, of which the following is a specification, reference being had to the accompanying drawing, forming part thereof.

Figure 1 is a front elevational view of a pressure control casing showing my new design;

Fig. 2 is a side elevational view, and

Fig. 3 is a top plan view thereof.

I claim:

The ornamental design for a pressure control casing substantially as shown.

PHILIP S. RUSSEL.
